REDUCTION OF KETONES

Philip J. Breivogel, Glen Ridge, N. J., assignor to
White Laboratories, Inc., Newark, N. J., a corporation of New Jersey

No Drawing. Application September 19, 1946,
Serial No. 697,917

18 Claims. (Cl. 260—613)

1

This invention relates to a method for the reduction of ketones, particularly to a method for the dimolecular reduction thereof to form pinacols. This application is a continuation in part of application Serial No. 640,137, filed January 7, 1946, now U. S. Patent No. 2,474,216.

The dimolecular reduction of ketones to pinacols is effected by submitting the ketone to the action of nascent hydrogen. The reduction has heretofore usually been effected with metals in aqueous acid solutions, electrolytically or with an amalgam of sodium, magnesium or aluminum in an anhydrous solvent for the ketone capable of acting as a hydrogen donor. These methods each possess certain inherent difficulties. Reduction with a metal and aqueous acid or electrolytically invariably leads to low yields and, particularly in the first instance, to the formation of secondary alcohols. The use of an aluminum or magnesium amalgam, although leading to higher yields, results in the formation of a mixture containing a voluminous precipitate of magnesium or aluminum hydroxide from which it is difficult to extract, or otherwise separate, the pinacol.

The preparation and use of sodium amalgam is difficult to carry out due to its highly reactive nature and its commercial use is impractical. The reducing agent heretofore employed most frequently has been aluminum amalgam. This amalgam, however, is difficult to prepare in a form having satisfactory activity and the reducing action of the amalgam under best conditions is undesirably slow. The preparation of aluminum amalgam in large quantities is especially difficult due to the critical conditions which must be maintained during its preparation. Inasmuch as the pinacols are intermediates in the preparation of many valuable products, it is apparent that any improvement in the method of their manufacture is desirable.

It is therefore an object of the present invention to provide a method for the dimolecular reduction of ketones to form pinacols.

An additional object is to provide a method for the preparation of a pinacol not subject to the difficulties of the heretofore known methods.

An additional object is to provide a method for the preparation of a pinacol by the dimolecular reduction of a ketone wherein the pinacol may be separated conveniently and in high yield from the reaction mixture.

An additional object is to provide a new reducing agent for the dimolecular reduction of ketones to form pinacols.

Other objects will become apparent as the description proceeds:

According to the present invention, the foregoing and related objects are accomplished readily and economically by reducing a ketone with an alloy of an alkali metal and lead in a solvent for the ketone capable of serving as a hydrogen donor and maintaining in the mixture an effective concentration of ions of an alkaline earth metal.

10 The term "alkaline earth metal" as used herein refers to the metals magnesium, calcium, barium and strontium.

The method of the invention offers certain advantages not possible to obtain when using the heretofore known reducing agents for ketones or when using a sodium-lead alloy in the absence of alkaline earth metal ions. In addition to the formation of pure pinacols in higher yields than heretofore obtainable, the reaction mixture is of such a nature that the pinacol may be recovered therefrom with ease. Due to the solubility of the salts of the alkali metals and to the solubility of many of the salts of the alkaline earth metals, reagents may be chosen, according to a preferred modification of the invention, to avoid the formation of undesired insoluble metal salts in the reaction mixture. The metallic lead remaining in the mixture settles readily and offers no problem of separation.

15 20 25 30 35 40 45 50 55 60 65 70 75 80 85 90 95 The alkaline earth metal ions may be introduced into the reaction mixture in a number of ways. The preferred way consists in adding an ion-producing salt or compound of an alkaline earth metal to the mixture or solution containing the ketone which is to be reduced. Only a very low concentration of alkaline earth metal ions in the solution is required and it appears that the effect is somewhat catalytic in nature. The presence of a moderately high concentration of alkaline earth metal ions in the mixture is not believed to be deleterious.

Alternatively, an alkaline earth metal may be incorporated in the alkali metal-lead alloy used in carrying out the reduction. In such case, sufficient of the alkaline earth metal is dissolved during the early stages of the reduction reaction to provide an adequate concentration of alkaline earth metal ions. Alloys containing from about .05 to about 2.5 per cent by weight of alkaline earth metal have been used with entire satisfaction.

The reduction may be carried out in acid, neutral or alkaline solution using water, aqueous alcohol or entirely organic solvents provided only that a hydrogen donor be present and that the

reaction mixture contain an ionizing solvent for alkaline earth metal compounds. When using water alone as the solvent a part only of the ketone may dissolve initially but the remainder dissolves as the reduction proceeds. Although the reduction may be effected with an alloy of lead with sodium, potassium, lithium or other alkali metal, a sodium-lead alloy is preferred for economic reasons and the invention will be described with particular respect thereto.

Sodium-lead alloys are prepared conveniently by melting sodium and lead together in the absence of air. The product is a brittle solid at ordinary temperatures and is preferably ground to a powder prior to being employed in reducing a ketone. It is conveniently preserved under hydrocarbon liquids or in an atmosphere of inert gases. In carrying out the reduction of a ketone, an alloy is used containing from about 5 per cent, or somewhat lower, to about 40 per cent, or somewhat higher, of alkali metal. Best results have been obtained using an alloy containing from about 8 per cent to about 15 per cent of sodium or other alkali metal.

When it is desired to use a sodium-lead alloy containing an alkaline earth metal, the alloy may be prepared as described previously and the alkaline earth metal incorporated prior to heating. In certain instances, it is desirable to pre-melt the alkaline earth metal with the lead prior to the formation of the sodium-lead alloy.

The method of the invention is applicable to the dimolecular reduction of a wide variety of ketones including dialkyl ketones, alkyl aryl ketones, diaryl ketones and alkyl aralkyl ketones as well as substitution derivatives thereof wherein the substituent is non-reactive under the reaction conditions. Ketones which are reduced successfully to pinacols utilizing the method of the invention include methyl ethyl ketone, propyl butyl ketone, hexyl ethyl ketone, methoxybutyl propyl ketone, benzophenone, methyl phenyl ketone, methoxyphenyl propyl ketone, hydroxyphenyl propyl ketone, methoxyphenyl butyl ketone, chlorophenyl propyl ketone, p - hydroxypropiophenone, p - methoxypropiophenone, methyl benzyl ketone, methyl chlorobenzyl ketone, ethyl tolyl ketone, p-chloropropiophenone, p-methoxybutyrophenone, butyl methoxybenzyl ketone, chlorobenzophenone, bromobenzophenone, and many others. A preferred embodiment of the invention relates to the reduction of alkyl aryl ketones, alkyl aralkyl ketones and their substitution products wherein the substituent group is nonreactive under the reaction conditions. Water-soluble salts of ketones containing a salt-forming radical may also be used.

In carrying out the reduction of a ketone according to the preferred modification, the ketone, solvent and alkaline earth metal salt are stirred together and the finely divided alloy added slowly. In case an alloy is used containing an alkaline earth metal, the addition of the soluble alkaline earth metal salt is, of course, unnecessary. Satisfactory results have been obtained by dissolving the ketone in alcohol, a mixture of glacial acetic acid and aqueous alcohol, aqueous alcohol, or water according to its solubility in such solvents. Water-insoluble ketones containing a functional group such as an hydroxy, carboxyl, or sulfo group, capable of forming a water-soluble salt, such as p-hydroxypropiophenone, may be converted to the salt and the reduction then car-

ried out in water and such variation is included within the scope of the invention.

Mixtures of alcohols, acids and other substances capable of serving as hydrogen donors with non-polar liquids such as benzene may be used, if desired, although such procedure is not usually desirable due to the tendency of the non-polar liquid to precipitate sodium salts during the course of the reaction. A hydrogen donor, as herein referred to, is any substance, liquid under the reaction conditions, capable of reacting with a sodium-lead alloy under such reaction conditions to furnish nascent hydrogen.

Although the reaction proceeds satisfactorily at low temperatures, e. g., at from 0° to 40° C., it may be carried out at temperatures as high as 100° C., or even higher. The reduction is usually complete in from a few minutes to several hours, depending upon the quantity of material being reduced, the temperature, the proportion of ketone to alloy, the degree of agitation of the mixture, and other factors. The reduction may be completed in from one to four hours. Somewhat more than the theoretical proportion of sodium, i. e., from 2.25 to 4.0 gram atoms of sodium for each mol of ketone, is usually employed to facilitate reduction of all of the ketone. The reaction mixture is preferably agitated vigorously throughout the reduction period.

Following the completion of the reduction, the metallic lead in the mixture is allowed to settle and removed by filtering or decanting and the liquid portion of the reaction mixture worked up in any convenient way to recover the pinacol therefrom. When the reduction is carried out in aqueous solution, the pinacol is conveniently recovered by extraction procedures or, in the case of the reduction of a water-soluble salt of a ketone containing a salt forming group, by acidifying the liquid reaction mixture and separating the pinacol by filtration or extraction with an organic solvent. When the reduction is carried out in an organic solvent, the pinacol may be recovered by evaporating the solvent or in any other convenient way. Purification of the crude pinacol may be effected by crystallization from a suitable solvent. Other ways of separating and purifying the pinacol will be apparent to those familiar with the art and the invention is not limited as to such methods of recovery or purification.

Certain advantages of the invention are apparent from the following examples which are given by way of illustration only and are not to be construed as limiting.

Example 1

A solution was prepared by dissolving 8 grams of sodium hydroxide and 30 grams of p-hydroxypropiophenone in 130 milliliters of water. The temperature of the solution was held at 15° to 20° C. and 105 grams of a powdered alloy consisting of 89.8 per cent lead, 10 per cent sodium and 0.2 per cent calcium was added with rapid stirring to the solution over a period of about one-half hour. The mixture was stirred for an additional one-half hour, the lead was allowed to settle and the supernatant liquid decanted. The lead residue was washed with sufficient water to bring the total volume of decanted liquid and washings up to 450 milliliters. Most of the excess sodium hydroxide in the solution was neutralized by adding 25 milliliters of acetic acid and the solution heated to about 60° C. and filtered. The clear filtrate was cooled to 15° C. and acidified

to litmus with acetic acid. After standing at room temperature for several hours, the precipitated, crude pinacol was recovered by filtering and washing with water and dried at 50° C. The product consisted of 24.9 grams of crude 3,4-bis(p-hydroxyphenyl)-3,4-hexanediol melting at 190° to 198° C. After washing the crude product with glacial acetic acid to remove resinous impurities, the dried product weighed 21.7 grams and melted at 192° to 200° C.

Example 2

A solution was prepared by dissolving 36 grams of p-hydroxypropiophenone, 3 grams of anhydrous calcium chloride and 8 grams of sodium hydroxide in 130 milliliters of water. The solution was stirred rapidly and 100 grams of a finely powdered alloy containing 90 per cent lead and 10 per cent sodium was added over a period of 45 minutes at 15° to 20° C. Stirring was continued for another hour, the lead was allowed to settle, the supernatant liquid was decanted and the lead residue washed with sufficient water to bring the total volume of decanted liquid and washings up to 350 milliliters. Most of the excess sodium hydroxide was neutralized by adding 20 milliliters of acetic acid and the solution was heated to 60° C. and filtered. The clear filtrate was cooled to 15° C. and acetic acid added slowly until the mixture reacted acid to litmus. After standing overnight, the crude pinacol was recovered by filtering and washing with water and dried at 50° C. The crude 3,4-bis(p-hydroxyphenyl)-3,4-hexanediol weighed 27.2 grams. The crude pinacol was washed with glacial acetic acid to remove unchanged p-hydroxypropiophenone and resinous impurities. The washed and dried product weighed 20.3 grams, had a melting point of 192° to 201° C. and was practically free of unchanged p-hydroxypropiophenone.

Example 3

Ninety-two grams of a finely powdered alloy, consisting of 89.7 per cent lead, 10 per cent sodium and 0.22 per cent magnesium, was added with rapid agitation over a period of fifteen minutes to a solution of 30 grams of p-hydroxypropiophenone and 8 grams of sodium hydroxide in 130 milliliters of water at 10° to 20° C. Stirring was continued at 20° C. for one-half hour after all of the alloy had been added. Most of the excess sodium hydroxide was neutralized by the addition of 20 milliliters of glacial acetic acid, and the fluid portion of the reaction mixture decanted from the lead residue and filtered at 60° C. The filtrate was cooled at 20° C., acidified to litmus with glacial acetic acid, and the crude pinacol which separated in solid form was removed by filtration, washed and dried. The dry crude product was washed with cold glacial acetic acid, then with cold water and dried. The dry product consisted of 18.6 grams of a mixture of the racemic and meso isomers of 3,4-bis(p-hydroxyphenyl)-3,4-hexanediol melting at 165° to 180° C.

Example 4

A solution was prepared by dissolving 8 grams of sodium hydroxide, 30 grams of p-hydroxypropiophenone and 3 grams of crystallized magnesium sulphate in 130 milliliters of water. The temperature of the solution was held at 10° to 15° C. and while stirring vigorously 120 grams of a powdered alloy containing 90 per cent lead and 10 per cent sodium was added over a period of

of 45 minutes. Stirring was continued for another 10 minutes, the lead was allowed to settle, and the supernatant liquid decanted. The lead was washed with sufficient water to bring the volume of the combined decanted liquid and washings up to 350 milliliters. Most of the excess sodium hydroxide in the solution was neutralized by adding 20 milliliters of acetic acid and the solution then filtered at about 60° C. The clear filtrate was cooled at 10° C. and acidified to litmus by adding acetic acid slowly and with stirring. After standing at 10° to 15° C. for about an hour, the precipitated, crude pinacol was recovered by filtering and washing with water and dried at 50° C. There was thus obtained 25 grams of 3,4-bis(p-hydroxyphenyl)-3,4-hexanediol melting at 187° to 198° C. After washing the crude product with glacial acetic acid to remove resinous impurities, the dried product weighed 22.4 grams and melted at 190° to 199° C.

Example 5

A solution was prepared by dissolving 8 grams of sodium hydroxide, 30 grams of p-hydroxypropiophenone and 4 grams of hydrated barium hydroxide in 130 milliliters of water. The solution was held at 10° to 20° C. and 108 grams of a powdered alloy containing 90 per cent lead and 10 per cent sodium was added with vigorous agitation over a period of about 35 minutes. Stirring was continued for another ten minutes, the lead was allowed to settle and the supernatant liquid was decanted. The lead residue was washed with sufficient water to bring the volume of the combined decanted liquid and washings up to 350 milliliters. Most of the excess sodium hydroxide was neutralized by adding 20 milliliters of acetic acid and the mixture then filtered at 60° C. The clear filtrate was cooled to 10° C. and acidified to litmus by adding acetic acid slowly with stirring. The mixture was allowed to stand at 10° to 15° C. for about an hour and the precipitated, crude pinacol recovered by filtering and washing with water and then dried at 50° C. There was thus obtained 24.4 grams of crude 3,4-bis(p-hydroxyphenyl)-3,4-hexanediol melting at 191° to 200° C. After washing the crude product with glacial acetic acid to remove resinous impurities, the dried product weighed 22.1 grams and melted at 192° to 202° C.

Example 6

A solution consisting of 30 grams of p-hydroxypropiophenone and 8 grams of sodium hydroxide in 130 milliliters of water was held at 15° to 20° C. and 100 grams of a finely powdered alloy consisting of 90 per cent lead and 10 per cent sodium was added over a period of 45 minutes with rapid agitation. No alkaline earth ion-producing substance was present in the reaction mixture. The reaction mixture was worked up as in Example 5 and there was thus obtained 17.4 grams of a mixture of meso and racemic 3,4-bis(p-hydroxyphenyl)-3,4-hexanediol melting at 165° to 186° C. and containing 18 percent of unchanged p-hydroxypropiophenone. The actual yield of pinacol was therefore 14.3 grams.

Example 7

A solution containing 30 grams of p-hydroxypropiophenone, 8 grams of sodium hydroxide and 3 grams of anhydrous calcium chloride in 130 milliliters of water was agitated rapidly at 20° to 25° C. and 90 grams of a finely powdered alloy

containing 70 per cent lead and 30 per cent sodium was added over a period of one hour. After stirring for another hour, the lead was allowed to settle, the supernatant liquid was decanted and the lead residue washed with sufficient water to bring the total volume of decanted liquid and washings up to 350 milliliters. Most of the excess sodium hydroxide was neutralized by adding 50 milliliters of acetic acid and the solution was heated to 60° C. and filtered. The clear filtrate was cooled to 15° C. and acidified slowly to litmus with acetic acid. The crude pinacol was recovered by filtering and washed with water and then dried at 50° C. The yield of crude 3,4-bis(p-hydroxyphenyl)-3,4-hexanediol so obtained weighed 26.5 grams. After washing thoroughly with glacial acetic acid, the dried product weighed 18.6 grams and melted at 160° to 181° C. Upon analysis, the washed and dried product was found to contain 37.4 per cent of unchanged p-hydroxypropiophenone. The actual yield of pinacol was therefore 11.7 grams.

Example 8

Thirty grams of p-hydroxypropiophenone was reduced with an alloy containing 70 per cent lead and 30 per cent sodium by the method of example 7, except that the calcium chloride was omitted from the reaction mixture. The yield of 3,4-bis-(p-hydroxyphenyl)-3,4-hexanediol, based on phenone-free product, was 5.1 grams.

Example 9

A solution consisting of 71.2 grams of p-methoxybutyrophenone and 6 grams of anhydrous calcium chloride in 600 milliliters of alcohol was agitated rapidly at 15° to 20° C. and 200 grams of a powdered alloy containing 90 per cent lead and 10 per cent sodium was added over a period of 45 minutes. The mixture was stirred for an additional 20 minutes at 20° to 25° C., the lead allowed to settle and the supernatant liquid decanted. The alcohol was distilled in vacuo from the decanted liquid. The oily residue remaining was washed with water to remove alkali, dissolved in ether and the solution dried with sodium sulfate. The dry ethereal solution was warmed gently to distill ether and the last traces of ether then removed in vacuo. The residue consisted of 62.5 grams of a clear, pale yellow, viscous oil which was found to be free of unchanged p-methoxybutyrophenone and which, upon analysis, was found to contain 94 per cent of 4,5-bis-(p-methoxyphenyl)-4,5-octanediol. The product was a mixture of meso and racemic isomers which were later separated in crystalline form by crystallization from a mixture of benzene and petroleum ether.

Example 10

One hundred grams of a finely divided sodium-lead alloy containing 10 per cent of sodium, and no alkaline earth metal, was added at 20° to 25° C. during one-half hour to a refluxing solution of 35.6 grams of p-methoxybutyrophenone in 300 milliliters of 80 per cent alcohol. The mixture was then refluxed for three hours and the alcoholic solution decanted from the lead residue. The alcohol was distilled from the solution and the residue crystallized from a mixture of benzene and petroleum ether. A 60 per cent yield of crystalline 4,5-bis-(p-methoxyphenyl)-4,5-octanediol was obtained. This comprised a mixture of the meso forms melting at 144° to 145°.

C. and a lower melting isomer, probably the racemic form, melting at 98° to 100° C.

Example 11

A solution containing 100 grams of propiophenone and 12 grams of crystallized magnesium sulfate in 960 milliliters of 80 per cent alcohol was agitated rapidly at 20° to 35° C. and 500 grams of a powdered alloy containing 90 per cent lead and 10 per cent sodium was added over a period of 45 minutes. The mixture was stirred for an additional 15 minutes and the lead allowed to settle. The clear, supernatant liquid was decanted and neutralized carefully with acetic acid and filtered. The alcohol was removed from the mixture by distillation in vacuo and the almost colorless, viscous residue washed with water to remove sodium acetate. The washed product was dried at 80° C. in vacuo. The dry product, which weighed 98 grams, was an almost colorless, very viscous oil. Upon analysis, the oil was found to contain 92 per cent of a mixture of meso and racemic 3,4-diphenyl-3,4-hexanediol. The meso form was isolated by crystallization from the alcohol and then melted at 137° to 137.5° C.

I claim:

1. The method for producing a pinacol which comprises contacting a ketone with an alkali metal-lead alloy under the influence of ions of an alkaline earth metal.
2. The method of claim 1, wherein the ketone is an aralkyl alkyl ketone.
3. The method of claim 1, wherein the ketone is an aralkyl aryl ketone.
4. The method of claim 1, wherein the ketone is water-soluble.
5. The method of claim 1 wherein the alkali metal-lead alloy is a sodium-lead alloy.
6. The method of claim 1 wherein the alkali metal-lead alloy contains from about 5 to about 40 per cent of alkali metal.
7. The method of claim 1 wherein the alkaline earth metal is calcium.
8. The method of claim 1 wherein the ketone is an alkyl aryl ketone.
9. The method of claim 1 wherein the ketone is p-hydroxypropiophenone.
10. The method of claim 1 wherein the ketone is p-methoxypropiophenone.
11. The method of claim 1 wherein the ketone is p-chloropropiophenone.
12. The method of claim 1 wherein the ketone is p-methoxybutyrophenone.
13. The method for producing a pinacol which includes contacting a mixture comprising a ketone, a hydrogen donor and an alkaline earth metal ion with an alkali metal-lead alloy.
14. The method of claim 13 wherein the hydrogen donor is water.
15. The method of claim 13 wherein the hydrogen donor is an organic liquid.
16. The method of claim 13 wherein the hydrogen donor is a solvent for the ketone and the alkaline earth metal ion.
17. The method for producing a pinacol which includes: contacting a ketone in a solution comprising a hydrogen donor and an alkaline earth metal ion with an alkali metal-lead alloy; and separating a pinacol from the reaction mixture.
18. The method for producing a pinacol which includes: contacting a solution comprising a hydrogen donor and a ketone with an alkali metal-lead alloy containing a minor proportion of an alkaline earth metal to effect conversion of at

least a part of the alkaline earth metal to alkaline earth metal ions; continuing the contacting of the ketone with the alkali metal-lead alloy under the influence of the so-formed ions; and separating a pinacol from the reaction mixture.
